UNITED STATES PATENT OFFICE.

LOUIS G. MASSICOTTE, OF PROVIDENCE, RHODE ISLAND, ASSIGNOR TO JULES H. FORTIER, OF WOONSOCKET, RHODE ISLAND.

PARING KNIFE.

Application filed December 7, 1923. Serial No. 679,254.

To all whom it may concern:

Be it known that I, LOUIS G. MASSICOTTE, a citizen of the United States, residing at Providence, in the county of Providence 5 and State of Rhode Island, have invented certain new and useful Improvements in Paring Knives, of which the following is a specification.

This invention relates to improvements in the construction of paring knives for fruit and vegetables; and has for its object to provide a knife of this character provided with a blade preferably formed of a single piece of sheet metal into substantially con- 10 cavo-convex shape in cross section, the blade having an elongated, open-sided slot extending along its body portion, one edge of the slot being sharpened and offset outwardly from the plane of the opposite or 15 guard edge thereof whereby when the slot becomes clogged it may be readily cleared by inserting the thumb of the hand holding the handle outwardly along the blade to force the clogging material out through 20 the end of the slot.

A further object of this invention is forming the blade with angular sides along its length for the purpose of stiffening the blade against bending and permitting it to 30 be made of very thin metal.

A further object of the invention is rounding and sharpening the end of the blade whereby it may be forced through the center of an apple to remove its core or 35 for cutting into vegetables to remove blemishes therefrom.

With these and other objects in view, the invention consists of certain novel features of construction, as will be more fully de- 40 scribed, and particularly pointed out in the appended claims.

In the accompanying drawings:—

Figure 1 is a top view of a knife showing the blade provided with an open-ended slot 45 and illustrating the shank of the blade as held in the handle shown partly in section.

Figure 2 is a section on line 2—2 of Figure 1 showing the angular shape of the sides of the blade; also showing one edge 50 of the slot as turned outwardly beyond the plane of the opposite or guard edge thereof.

Figure 3 is a sectional side elevation taken on line 3—3 of Figure 1.

It is found in the practical construction 55 and operation of a paring knife of this

character of advantage to form the blade from a single piece of sheet metal, the same being constructed into substantially con- 60 cavo-convex shape in cross section, and to form a slot which extends along the length 60 of the knife and through its end; also to form the blade of a length substantially that of the ordinary thumb whereby when the slot becomes clogged with parings a simple movement of the thumb outwardly 65 along the blade drives the clogging material out through the open end of the slot thus readily clearing the same; and the following is a detailed description of one construction of blade by which these advan- 70 tageous results may be accomplished.

With reference to the drawings, 10 designates the blade of my improved paring knife which is preferably formed of sheet steel, the blade proper being preferably of 75 a length substantially that of the ordinary thumb and the blade being struck into con- cavo-convex shape with its end 11 being preferably sharpened whereby the blade may be forced through an apple to remove 80 its core or the end may be forced into blemishes in vegetables to remove the same.

This blade is provided with a slot 12 formed substantially the length of the blade, the slot being open at its outer end as at 85 13, the blade at the inner end of this slot being provided with an elongated, trans- verse opening 14 and one edge 15 of this slot is sharpened and turned or bent out- 90 wardly from the plane of the opposite or guard edge 16 whereby this edge 16 serves to limit the depth of cut of the paring or projecting edge 15.

One edge 17 of this blade may also be sharpened if desired to be used as an ordinary cutting edge.

In order to stiffen this blade, I have pro- 95 vided the same with angular side walls, that is a somewhat sharp angle 18 is formed in each of the side walls of the blade which 100 serves to greatly stiffen the blade to permit it to be formed of stock much thinner than could otherwise be used.

This blade is provided with a shank 19 formed broad at its inner end 20 to ex- 105 tend into the handle 21 to prevent the blade from turning in the handle.

It will be noted that my improved blade is formed complete of a single piece of sheet metal and that the blade is of a length so 110

short that the thumb of the hand holding the handle may be readily slid along the inner or grooved face of the blade outwardly to force the clogging material from 5 the slot out through the end thereof to readily clear the same which effect cannot be produced with the knife blade which is not provided with an open ended slot.

My improved knife is very simple and 10 practical and inexpensive in construction and effective in its operation and by its use vegetables may be pared with the minimum amount of waste, the end of the blade may be used for removing blemishes in the vegetables and the cutting slot may be readily cleared by a simple movement of the thumb when clogged.

The foregoing description is directed solely towards the construction illustrated, but 20 I desire it to be understood that I reserve the privilege of resorting to all the mechanical changes to which the device is susceptible, the invention being defined and limited only by the terms of the appended 25 claims.

I claim:

1. A paring knife comprising a blade formed of a single piece of sheet metal of substantially concavo-convex shape in cross 20 section and having a slot running longitudinally of the blade and through one of its ends, one of the edges of the blade adjacent the slot lying in a different plane from the edge of the blade adjacent the opposite edge of the slot.

2. A paring knife comprising a blade formed of a single piece of sheet metal of substantially concavo-convex shape in cross 40 section and having an open ended slot at approximately the median line thereof and extending longitudinally of the blade, the edge of the blade adjacent one side of the slot lying in a different plane from the edge

of the blade adjacent the opposite side of the slot, one of said edges being sharpened, 45 strengthening portions of the blade lying between the slot and the outer edges of the blade.

3. A paring knife comprising a blade formed of a single piece of sheet metal of 50 substantially concavo-convex shape in cross section and having an open ended slot approximately along the median line of the blade with the edge of the blade adjacent one side of the slot lying in a different plane 55 from the edge of the blade adjacent the opposite edge of the slot, the outer end of the blade being formed arcuate and sharpened into a cutting edge.

4. A paring knife comprising a blade 60 formed of a single piece of sheet metal of substantially concavo-convex shape in outline, having a slot extending longitudinally thereof and through one end, one of the edges of the blade adjacent the slot lying 65 in a different plane from the edge of the blade adjacent the opposite edge of the slot, a portion of the blade lying between the slot and the outer edges of the blade being angularly formed and the outer edges of the 70 blade sharpened.

5. A paring knife comprising a blade formed of a single piece of sheet metal and having a slot extending longitudinally thereof and through one end, one of the edges of 75 the blade adjacent the slot lying in a different plane from the edge of the blade adjacent the opposite side of the slot, the first named edge being sharpened to form a cutting edge, the blade having angular portions extending longitudinally thereof and intermediate the slot and the outer edges of the blade, said outer edges being also sharpened to form a cutting edge.

In testimony whereof I affix my signature.

LOUIS G. MASSICOTTE.
